Claims priority, application Sweden February 11, 1957

Term of patent 14 years

(Cl. D9—2)

Fig. 1.

Fig. 2.

Fig. 3.

Fig. 4.

Fig. 6.

Fig. 5.

Fig. 1 is a perspective view of a suction cleaner showing our new design;

Fig. 2 is a rear perspective view thereof;

Fig. 3 is a front elevational view thereof;

Fig. 4 is a rear elevational view thereof;

Fig. 5 is a side elevational view thereof; and

Fig. 6 is a top plan view thereof.

The dominant features of our design reside in the portions shown in full lines.

We claim:

The ornamental design for a suction cleaner, as shown and described.
